UNITED STATES PATENT OFFICE.

LOUIS E. COOK, OF MILWAUKEE, WISCONSIN.

RECORD-DUSTING BRUSH.

Application filed February 13, 1922. Serial No. 526,204.

To all whom it may concern:

Be it known that I, LOUIS E. COOK, a citizen of the United States, residing at Milwaukee, in the county of Milwaukee and 5 State of Wisconsin, have invented certain new and useful Improvements in Record-Dusting Brushes, of which the following is a specification, reference being had to the accompanying drawings.

10 It is well known that talking machine records, even though in cabinets or record racks, collect more or less dust. When the record is played, the dust collects around the stylus, and therefore produces an inferior reproduction of the record.

It is, therefore, the purpose to provide a device of the present character, for removing the dust from the face of the record while it is in the act of reproducing.

20 There are pads, which are manually operated, and others which are carried by the sound box or reproducer, or by the tone arm. There are also brushes used on the reproducer or tone arm.

25 It has been found that the brushes which are carried by the reproducer and by the tone arm are at all times operating on the record, until the playing of the record is completed. It has also been discovered that 30 the pads made of felt or other material merely sweep over the surface of the sound wave grooves, and do not enter the grooves.

Therefore, it is another purpose to provide a brush manually actuated and adapted to sweep the entire record during one or 35 two revolutions of the record, and since the bristles are more or less pliable, their terminals will engage within the sound wave grooves, and thereby remove the dust 40 and dirt, and no doubt, enable the record to be reproduced with a clear tone.

Also in devices which have heretofore been used the pad or brush is rigid with respect to the handle or with respect to the 45 reproducer or tone arm, and for this reason the felt or bristles will also sweep over the sound wave grooves, without entering the grooves.

Hence, a still further purpose consists in 50 the provision of a brush, which is loosely mounted with respect to the handle, so that it can swirl or rotate in various positions as the record turns, in fact accommodate itself to the movement of the record, and since

the brush is long enough to extend from 55 where the sound wave groove begins to its extreme outer terminal groove, the record may be easily swept or cleaned in one, two or three revolutions of the record.

Additionally the invention aims to provide a brush of this character, wherein the screw on which the handle is swivelly mounted, is engaged through the handle, so that its head will engage with the shoulder formed below the outer end of the 65 handle, so as to prevent detachment of the handle.

It is also possible with the present form of brush, to hold the brush stationary with respect to the handle by means of the hand 70 of the operator, and enable the brush to sweep the felt of the turntable. Furthermore the securing screw may be tightened, so as to hold the wood portion of the brush stationary with respect to the 75 handle, so as to avoid the operator manually holding the brush stationary with respect to the handle, when sweeping the turntable.

The brush, unlike those which are carried by the reproducer or tone arm, may be 80 disposed, when not in use, in one corner of the top of the cabinet out of the way of the turntable, and in this case the brush is always handy, for the purpose of dusting the records, or for sweeping the face of 85 the turntable.

Obviously the handle or the wood portion of the brush together with the bristles, or the screw may be easily renewed, by replacing them with others, thereby avoiding the 90 owner of a talking machine purchasing an entire new brush, when such is necessary.

While the design and construction at present illustrated and set forth are deemed preferable, it is obvious that as a result of 95 a reduction of the invention to a more practical form for commercial purposes, the invention may be susceptible of changes, and the right to these changes is claimed, provided they are comprehended within the 100 scope of what is claimed.

The invention comprises further features and combination of parts, as will be herein-after set forth, shown in the drawings and claimed.

In the drawings:—

Figure 1 is a view, showing a record mounted on the turntable of a talking ma-

chine, and the brush held in position, for the purpose of brushing the grooves of the record;

Figure 2 is a longitudinal sectional view 5 through the brush and the handle; and

Figure 3 is a cross sectional view on line 3—3 of Figure 2.

Referring to the drawings, 1 designates 10 the wood portion of the brush, which may be any suitable length, thickness or depth. In fact the wood portion of the brush may be any proportions, preferably of a length to enable the brush to extend from where the sound wave groove begins, to its terminal, or slightly further, in order that the 15 full surface of the sound wave groove, and space intermediate the grooves may be swept in several revolutions, say for instance about three, more or less. The wood portion of the brush may be any suitable shape, and the bristles 2 constructed of any suitable hair, preferably camel's hair, which is very light and soft, and which will not mar, scratch or otherwise injure the sound wave 20 grooves of the record.

A handle 3 is provided, and may be any 25 suitable shape, length or diameter, preferably as shown. The handle has a bore 4, through which an elongated screw 5 engages, and is threaded into the wood part of the brush. The outer end of the bore of the handle is countersunk, thereby causing to be 30 formed a shoulder 6, with respect to which the head 7 of the screw may be normally spaced. In other words when holding the handle firm and the terminals of the bristles of the brush are resting upon the record, the handle is held, so that there is a looseness of play between the wood portion of the 35 brush and the handle. For instance the handle will be held firm so as to enable the brush to easily and freely swirl with respect to the handle. Obviously the handle is swiveled on the brush, enabling the brush to freely 40 rotate while the handle is held firm in the operator's hand. Obviously the operator may grasp the handle, and a portion of the

wood of the brush, and hold the two stationary with respect to each other, enabling the operator to hold the brush, whereby it 50 may be used for sweeping the felt of the turntable. In order to accomplish this result without the operator holding the wood portion of the brush with respect to the stationary portion of the handle, the screw 55 may be tightened, so that the head of the screw may tighten against the shoulder and hold the brush with respect to the handle. However, the brush is mounted to move freely with respect to the handle, or the 60 handle swiveled with respect to the brush, and in this way enabling the brush to easily swirl, while the handle is held fast in the hand of the operator. In this way the brush is allowed to accommodate itself to the 65 movement of the record, enabling the terminals of the bristles to project into the grooves and thereby remove all the dust.

The invention having been set forth, what 70 is claimed is:

A record cleaning brush comprising a handle adapted to be grasped and held rigid in the hand of an operator, a brush body provided with a threaded socket and having bristles to sweep over and into the record 75 grooves, said handle having a bore formed therethrough from one end to the other, the outer end of said bore being countersunk, a screw engaging through said bore loosely, whereby it may rock therein and having its head engaging the bottom of the countersink at the outer end of the bore, the shank of the screw having one end tapered and adjustably connected within said threaded socket and adapted to be adjusted to 80 hold the handle fixed relatively to the brush body, or adjusted so that the screw may rock or rotate in the bore, whereby the bristles may swirl with respect to the record, and allow the bristles to accommodate themselves to the record grooves.

In testimony whereof I hereunto affix my signature.

LOUIS E. COOK.
